(57) CLAIM

(21) Appl. No.: 29/114,087

The ornamental design for a sunshade and a mirror of a truck vehicle, as shown and described.

(22) Filed: Nov. 17, 1999

DESCRIPTION

(51) LOC (7) Cl. 12-16

FIG. 1 is a perspective view of a sunshade and a mirror of a truck vehicle showing our new design;

(52) U.S. Cl. D12/191

FIG. 2 is a front view of the invention shown in FIG. 1; it may be understood that the broken lines on all figures are for illustrative purposes only and form no part of the claimed design;

(58) Field of Search D12/191, 187,

FIG. 3 is a right side view of the invention shown in FIG. 1; FIG. 4 is a left side view of the invention shown in FIG. 1; FIG. 5 is a top view of the invention shown in FIG. 1; FIG. 6 is a bottom view of the invention shown in FIG. 1; and,

D12/188, 181-182; 296/97.1-97.12, 95.1,

FIG. 7 is a back view of a sunshade and a mirror of a truck vehicle showing my new design.

91, 180.1; 180/68.6; 362/80.1; 160/370.21,

371, 105, 354, DIG. 3
